UNITED STATES PATENT OFFICE.

GEORGE W. DRYER, OF GARDINER, NEW YORK, ASSIGNOR, BY MESNE ASSIGNMENTS, TO AMERICAN MOTOR BODY COMPANY, OF DETROIT, MICHIGAN, A CORPORATION OF DELAWARE.

CAR-SEAT.

1,389,130.

Specification of Letters Patent. Patented Aug. 30, 1921.

Application filed January 19, 1920. Serial No. 352,342.

To all whom it may concern:

Be it known that I, GEORGE W. DRYER, a citizen of the United States, residing at Gardiner, in the county of Ulster and State of New York, have invented certain new and useful Improvements in Car-Seats, of which the following is a specification.

My invention relates to railway car seats, and my object is to provide a seat of a broadly new type which will be light of weight, by which maximum cushion space will be secured for a given over-all length and in which a minimum number of parts will be used. An additional object is to provide a construction in which all of the space underneath the seat is entirely free and unimpeded by mechanism or frame work.

I attain these objects by a construction in which supports are provided, with a pair of members mounted on the supports and adapted to be positioned, one as a seat and the other as a back at one side of the construction, from which positions the members may be moved together, so that the back member becomes the seat and the seat member becomes the back at the other side of the construction. This result may be achieved by the provision of two similar members, each of which is adapted to serve either as a seat or as a back, these members being pivoted at the front and back of the construction. Connections are provided between these members such that when one of the members rests in seating position the other one will extend upwardly from its pivot in the correct position to serve as a back. When it is desired to reverse the seating direction of the seat, the member which is serving as a back may be swung downwardly about its pivot into position to serve as a seat, the other member rising at the same time from its seating position into position to serve as a back at the opposite side of the construction.

In the preferred form of device connection is made between the seat and back members by a pair of links, one at each end of the construction, which links are pivotally connected at their ends to the end surfaces of the seat and back members at points which are not far distant from the pivotal connections between the said members and their supports. The pivotal connections between these links and the two members re-

ferred to are so chosen as to serve two purposes. One of these is to enable the downward pivotal movement of the back member into the seating position to cause the other member to rise from the seating position to the back position on the other side of the construction. This effect takes place because of the fact that the pivotal connection between the link and the member in seating position is somewhat above the pivotal connection of the member in seating position with its supports, so that a leverage is exerted on this member by the link when the other member swings downwardly into seating position. The other function performed by the links is to prevent either member, when in its position to serve as a back, from swinging rearwardly beyond its correct back position. When either member is in its position to serve as a back, the pivotal connection of the levers with this member is some distance above the pivotal support of the member. A movement of the member in its back position toward a position still further in the rear is prevented by direct pull through the links to their pivots at their other ends, the other member being firmly seated at this time on its seat supports.

With this construction it will be noted that the links and the seat or back members are the only moving parts, and that the links may be located to a large extent between the member which is in seating position and the adjacent aisle end plate or wall end plate. It will also be noted that it is not possible to move the back while the seat is occupied.

In order that a clearer understanding of my invention may be had, attention is hereby directed to the accompanying drawings forming part of this application and illustrating one embodiment of my invention. In the drawings, Figure 1 represents an end elevation of a construction embodying my invention; Figs. 2 and 3 are sections taken respectively on lines 2-2 and 3-3 of Fig. 1; Fig. 4 is a front elevation of the construction; and Fig. 5 is an enlarged detail of construction shown partly in front elevation and partly in section.

Referring to the drawings, the structure is illustrated as supported from a pedestal 1 at the aisle end and a support at the wall end, which is indicated at 2. Angular members 3, 3, are mounted on pedestal 1 and

100

105

110

support 2 to serve as cover plates. Angular members 4, 4, are mounted on the bottom flanges of members 3, 3, members 4, 4, having horizontal flanges 4' extending inwardly 5 of the structure and vertical extensions 4² of the vertical portions of members 4, extending above the inwardly extending flanges 4'. Flanges 4' have screws 5 extending therethrough, these screws being 10 provided with rounded heads 6 on the upper surface of flanges 4'. These rounded heads 6, preferably four in number, one each at the front and rear of the aisle and wall ends of the construction, are adapted to 15 serve as seat supports. The various supporting members referred to are preferably formed of steel.

The seat and back are formed by a pair 20 of members 7 and 8, which may be substantially duplicates of each other and are each adapted to serve either as seat or back cushions. Metal blocks, preferably iron castings, 9, 9, are set into the end surfaces of seat and back members 7 and 8 to serve as 25 pivot supports.

The members 9 at the left hand end of the seat cushion, referring to Fig. 1, are provided with bosses 9' which are pivotally mounted within suitable openings in the 30 vertical upward extensions 4² of the end supports 4. As is shown in Fig. 1, the seat cushion 7 is adapted to lie in seating position upon the seat supports 6. The back cushion 8 is similarly pivoted, the bosses 9' 35 of its blocks 9 being similarly mounted in the vertical extensions 4² at the right hand side of the structure, referring to Fig. 1. The cover plate 3 may be secured to the outer end of bosses 9' at each end of the 40 structure by means of screws 10 and heads 11.

The blocks 9 are also provided with bosses 9² on which the links 12, one at each end of the structure, are pivoted. Screws 13, having heads 14, may be extended through bosses 9² into the members 7 and 8, washers 15 being mounted between bosses 9² and heads 14.

The links 12 are of such a length, and the 50 points of their pivotal connections with members 7 and 8 are so chosen, that when member 7 rests upon supports 6 to act as a seat cushion, member 8 is in correct position to act as a back cushion, and when member 55 8 rests on supports 6 to act as a seat cushion, member 7 will be in the correct position to act as a back cushion at the opposite side of the structure, this position being indicated in dot and dash at the left of Fig. 1.

60 The bosses 9' of blocks 9 are provided with portions 9³ of enlarged diameter, adjacent to the end surfaces of members 7 and 8. Links 12 are provided on their lower surfaces with curved recesses 16 adjacent 65 to the ends of the links. These recesses are so

positioned that the one adjacent the right hand end of the link 12, referring to Fig. 1, will seat itself upon the boss 9³ of the adjacent block 9 when member 8 is in position to act as a back cushion, and recesses 16 adjacent the left hand end of the link will seat themselves upon the boss 9³ at the left hand end of the structure when the member 7 is in position to act as a back cushion. 70

Referring to the position of the parts indicated in Fig. 1, it will be noted that the pivotal connection between link 12 and seat member 7 is located somewhat above the pivotal connection between the member 7 and supports 4². Accordingly, when the 80 back cushion 8 is swung downwardly to the left into position to act as a seat cushion, leverage will be exerted on member 7 by links 12 to raise the member 7 into position to act as a back cushion. Links 12 are preferably given the form of a compound curve as illustrated, so as to keep the same largely hidden behind the end supports. It will also be noted that the member which acts as back cushion, such as the member 8, is prevented from moving rearwardly from its correct position by the links 12. Any force tending to move member 8 to the rear from its correct position as a back cushion merely acts through the links 12 and the pivotal 95 connections between the links and the member 7 to transmit the force to the iron pivot blocks 9 of member 7 or to force member 7 more firmly against its seat supports 6. Movement of the back cushion 8 in the opposite direction, to reverse the seating direction of the seat, is, of course, impossible 100 when the seat is occupied.

The intermediate positions of members 7 and 8 on the reversal of the seating direction of the seat are indicated in dotted lines in Fig. 1, in which it will be noted that the leverage of links 12 is so chosen as to cause the seat cushion to rise with sufficient rapidity to cause the same to clear the descending 110 back cushion.

The particular form of seat and back cushion to be used is not material for the present invention and is, therefore, not illustrated, it only being essential that one side 115 of each member shall be adapted to act as a seat cushion and the other side as a back cushion. Members 7 and 8 may be, for example, of wooden slat construction, double panel, or they may be otherwise formed and 120 shaped with suitable upholstery, if desired.

It will be noted that all of the space underneath the seat is absolutely unencumbered from the inside of pedestal 1 to the wall of the car. It is, therefore, possible to mount 125 connecting rails for the support of heaters between the aisle and wall plates, and to mount a foot rail between the pedestal and the wall of the car, if desired. With the construction illustrated the vertical move- 130

ment of links 12 is comparatively slight, as is indicated in Fig. 1. It will be noted that the construction described makes an extremely light structure possible with a very slight space requirement for mechanism at each end of the seat cushion, so as to provide a maximum cushion space for a given over-all length.

What I claim is:—

10 1. In a car seat, the combination of supports, a pair of similar members pivotally secured to said supports at opposite sides thereof and each adapted to be positioned as a seat when the other is positioned as a back, and means independent of said supports for causing the movement of one member from seat to back position automatically in consequence of the movement of the other from back to seat position due to pressure applied thereto in a generally horizontal plane.

2. In a car seat, the combination of supports, a pair of similar members pivotally secured to said supports at opposite sides thereof and each adapted to be positioned as a seat when the other is positioned as a back, and means independent of said supports for causing the movement of one member from seat to back position automatically in consequence of the movement of the other from back to seat position due to pressure applied to either member.

3. In a car seat, the combination of supports, a pair of similar members pivotally secured to said supports at opposite sides thereof, each adapted to serve as either back or seat, and link connections independent of said supports and extending directly between said members, the organization being such that when either member is positioned as a seat the other member will be positioned as a back, and when the latter is, due to pressure applied thereto, swung downwardly to act as a seat, the former will automatically be swung upwardly on the opposite side to act as a back, the pivotal connections between said links and members being so located that downward movement of a member from back position causes said link connections to push upon said other member at a point above the pivotal connection thereof with said supports.

4. In a car seat, the combination of supports, a pair of similar members pivotally secured to said supports at opposite sides thereof, each adapted to serve as either back or seat, and links connecting said members, each link being pivoted at its ends to said members at points which are above the pivotal connections between said members and supports in all positions of said members, said link pivots being so located that when one member is positioned as a seat the other will be positioned as a back, and when the latter is swung downward to act as a seat

leverage will be exerted through said links on the former to swing the same upwardly on the opposite side to act as a back.

5. In a car seat, the combination of end supports, members, each adapted to serve as seat or back, pivoted thereto at the front and rear, to swing between the same, seat supports secured to said end supports and extending inwardly therefrom, and links at the opposite ends of the seat, pivotally connected at their ends to the ends of said members at points which are above the pivotal connections between said members and supports in all positions of said members, said points being so located that when either member is in seating position the other member will be in position to serve as a back, said links being located between said members and end supports.

6. In a car seat, the combination of end supports, having openings therein, members, each adapted to serve as seat or back, blocks secured to the ends of said members, having bosses thereon, mounted in said openings to serve as pivots at the front and rear, between which said members are adapted to swing, said blocks having a second set of bosses, links at the opposite ends of the seat, each link being pivotally connected at its opposite ends to said second bosses of said two members and seat supports, said second bosses being above said first bosses in all positions of said members, and so located that when one member is positioned as a seat the other will be positioned as a back, and when the latter is swung downwardly to act as a seat, leverage will be exerted through said links on the former to swing the same upwardly on the opposite side to act as a back.

7. In a car seat, the combination of end supports, having openings therein, members, each adapted to serve as seat or back, blocks secured to the ends of said members, having bosses thereon, mounted in said openings to serve as pivots at the front and rear, between which said members are adapted to swing, said bosses having enlarged portions adjacent the end surfaces of said members, said blocks having a second set of bosses, links at the opposite ends of the seat, each link being pivotally connected at its opposite ends to said second bosses of said two members, and seat supports, said second bosses being above said first bosses in all positions of said members, and so located that when one member is positioned as a seat the other will be positioned as a back, and when the latter is swung downwardly to act as a seat leverage will be exerted through said links on the former to swing the same upwardly on the opposite side to act as a back, said links having curved recesses on their lower surfaces adjacent their ends, so located that when one of said members is in back position, said recesses adjacent thereto will seat on said enlarged portions of said first named bosses.

8. In a car seat, the combination of end supports having inwardly extending flanges and vertical extensions above the same, seat supports on said flanges, cover plates outside 15
5 said end supports, members, each adapted to serve as seat or back, pivoted to said vertical extensions at front and rear, to swing between the same, and links connected at their ends to the ends of said members, at points 10 above the pivotal connections between said members and supports, said points being so

located that when either member is in seating position the other member will be in position to serve as a back, said members being formed with compound curves so as to be largely hidden by said cover plates.

This specification signed and witnessed this 9th day of January, 1920.

GEORGE W. DRYER.
